KNURLING TOOL

Merrill E. Williams, 162 Chelsa St.,
Stratford, Conn. 06497

Filed June 8, 1970, Ser. No. 23,360

Term of patent 14 years

Int. Cl. D8—05

U.S. Cl. D8—51

FIG. 1

FIG. 2

FIG. 3

FIG. 7

FIG. 4

FIG. 5

FIG. 8

FIG. 6

FIG. 1 is a perspective view, as seen from its forward end, of a knurling tool, showing my new design;

FIG. 2 is a perspective view as seen from the rearward end;

FIG. 3 is a top plan view;

FIG. 4 is a side elevational view showing one side of the tool;

FIG. 5 is a bottom plan view;

FIG. 6 is a side elevational view showing the opposite side of the tool from the side shown in FIG. 4;

FIG. 7 is a front end view on an enlarged scale; and,

FIG. 8 is a rear end view, also on an enlarged scale.

I claim:

The ornamental design for a knurling tool, substantially as shown.
